TYPE-WRITING MACHINE.

Specification of Letters Patent.

Patented Nov. 7, 1916.

Application filed January 16, 1914. Serial No. 812,433.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to typewriting machines adapted to write different languages in which the lines of one language are written or printed in the reverse direction from those of the other language. In certain languages, as for example Hebrew or Arabic, the lines of writing or printing run from the right toward the left, instead from left to right as in English and other modern languages.

In accordance with the present invention, a paper carriage may be driven in either direction, and two sets of types representing languages in which the lines of writing run in opposite directions, may coöperate with letter-feeding mechanism to control the travel of the carriage, and permit a letter-feed movement of the carriage in the direction corresponding to the language being written.

In carrying out the invention, the paper carriage is shifted from one set of types to another set, each set having its own keys. The type sets may be placed side by side and the carriage may run upon a track of sufficient length to enable it to coöperate with the other set of types. The types of one set may comprise characters of a language, the lines of which are written and read from left to right as for example, the English language, and the types of the other set comprise the characters of a language written from right to left. Means for driving the carriage in either direction, depending upon which language is being written, may comprise spring drums or motors adapted to be selectively connected by draw bands to the carriage. When the carriage is moved into a position to coöperate with one set of types it is automatically connected with a motor for driving the carriage in the letter-feeding direction required in writing the language represented by said types. When the carriage is shifted to the zone of the other set of types it is automatically disconnected from the first motor and connected to the other motor to be driven in the reverse direction.

The carriage may be connected to the motors through draw bands and hooks on the ends of the draw bands held in position to be picked up by lugs on the carriage, each motor being thus connected to the carriage as the latter is moved into the printing zone corresponding to said motor. Separate letter-feed mechanisms may control the letter-feed movements of the carriage in opposite directions, and letter-feed rack bars may be mounted on the carriage and may have their teeth faced in opposite directions, one rack coöperating with an escapement mechanism permitting a feed of the carriage from right to left, and the other rack coöperating with an escapement mechanism for feeding from left to right.

Other objects and advantages will herein-after appear.

In the accompanying drawings, Figure 1 is a perspective plan view of a machine constructed in accordance with the principles of my invention. Fig. 2 is a sectional view of the feed racks and the left hand escapement wheel. Fig. 3 is a similar view showing the escapement wheel at the right hand side of the machine. Fig. 4 is a detail perspective view of a spring motor and means for automatically connecting and disconnecting it to and from the carriage. Fig. 5 is a sectional side elevation, the section being near the center of the right hand machine Fig. 1. Fig. 6 is a rear elevation, the carriage being shifted to the opposite end of the tracks from the position shown in Fig. 1. Fig. 7 is a detail sectional plan showing the spring motors and draw bands. Fig. 8 is a detail view of a hook to be connected to a draw band. Fig. 9 is a view similar to Fig. 6 but with the carriage in an intermediate position.

In practising the invention in the form illustrated, the frameworks 1 and 2 of two Underwood front strike typewriting machines may be rigidly mounted on a common base 3 and may also be rigidly connected by front and rear carriage rails 4 and 5, each of which rails extend from the left hand end of the frame 1, to the right hand end of the frame 2. A paper carriage 6, which may be an Underwood typewriter carriage of the usual construction, is mounted for travel on the rails 4 and 5, rolls 7 on the carriage running in a groove in the rail 4, and bearing lugs 8 on the carriage, slidable on the rear rail 5. A rotary platen

9 is mounted in a platen frame which may properly guided into interlocking position. 10 is connected by the usual means to the right out paper shelf 11 to the carriage the platen, of which zone of the left-hand type-bar system said platen frame mounted to shift on the ten, the hook 34 is brought up against a 5 carriage to upper and lower case positions. 11 through the band 33 is 70

The frame 2 is provided with a set of types 12 which may be printed in the characters of the English language, or any other language, written from left to right, on the work- 75 sheet, said types being actuated by keys 13 mounted on key levers 14, the keys 13 being an extension of a frame 15 in which the left-hand escapement mechanism is mounted. 80 being held depressed manually while the type keys are struck, and the shift key 52 provided with the usual means for locking it in depressed position while in use.

5. The left-hand keyboard 19 may be provided with shift keys 56 and 57 which operate in the same manner as the keys 51 and 52, to actuate the shift rail 58 for lifting the carriage when the latter is in the left-hand printing zone.

When the carriage is in the right-hand printing zone, its position at the beginning of a writing line is determined by a margin stop 59 adjustable along a rod 60 and carrying a pointer 61 moving over a scale 62 on the front rail 4 to indicate the position of the stop. A similar stop 63 carrying a pointer 64 moving over a scale 65, serves a like purpose when the carriage is in the left-hand zone. That is, in each instance the stops 59 and 63 determine the position of the carriage at the beginning of a line of writing. It will be noted that the two scales 62 and 65 read in opposite directions, to agree with the opposite letter-feed movements of the carriage.

Variations may be resorted to within the scope of the invention, and portions of the improvements may be used without others.

30. Having thus described my invention, I claim:

1. In a typewriting machine, the combination, with a carriage; of mechanism for effecting a letter-feeding movement of the carriage in one direction; a bank of keys for actuating said mechanism; mechanism separate from the first-named mechanism for effecting a letter-feeding movement of the carriage in the opposite direction; and a bank of keys separate from the first-named bank for actuating the second-named mechanism.

15. In a typewriting machine, the combination, with a carriage arranged to travel in either direction; of means to drive the carriage; letter-feed mechanism to control the movement of the carriage in one direction; and letter-feed mechanism independent of and remote from the first-named mechanism to control the movement of the carriage in the opposite direction.

20. In a typewriting machine, the combination with a traveling carriage arranged to travel in opposite directions, of two sets of types, means for driving the carriage, means actuated by the types of one set for controlling the letter-feed movement of the carriage in one direction, and means actuated by the types of the other set for controlling the letter-feed movement of the carriage in the reverse direction.

25. In a typewriting machine, the combination with a traveling paper carriage arranged to travel in opposite directions, of means to drive the carriage, two sets of types comprising the characters of two languages in which the lines are written in opposite directions, a set of type keys for each set of types, letter-feeding mechanism actuated by one set of type keys for controlling the travel of the carriage in one direction, and letter-feeding mechanism actuated by the type keys of the other set for controlling the movement of the carriage in the opposite direction.

75. In a typewriting mechanism, the combination with a plurality of type systems, of means for letter-spacing a work-sheet in one direction when the types of one system are actuated, and means for letter-spacing a work-sheet in the reverse direction when the types of the other system are actuated.

80. In typewriting mechanism, the combination with a plurality of sets of types and keyboards comprising a set of keys for each set of types, of means actuated by the keys of one set for letter-spacing a work-sheet in one direction, and means actuated by the keys of the other set for letter-spacing a work-sheet in the reverse direction.

85. In a typewriting mechanism, the combination with a plurality of type systems and a paper carriage adjustable to coöperate with either type system, of means to impart letter-feeding movements to the carriage in one direction when coöoperating with one type system, and means to impart letter-feeding movements to the carriage in the reverse direction when coöoperating with the other type system.

90. In a typewriting mechanism, the combination with a plurality of type sets, of a paper carriage adjustable to coöperate with either type set, means for driving the carriage in one direction when coöoperating with one type set and in the opposite direction when coöoperating with the other set, letter-feeding mechanisms respectively controlling the letter-feeding movements of the carriage in said directions, and means to automatically bring the carriage under the control of the feeding mechanism corresponding to the type set with which the carriage is positioned to coöperate.

100. In a typewriting machine, the combination with a traveling carriage, of a motor for driving the carriage in one direction, a motor for driving the carriage in the opposite direction, and means operable by the movement of the carriage to disconnect it from one motor and connect it with the other motor.

105. In a typewriting machine, the combination with a traveling carriage, of a motor for driving the carriage in one direction, a motor for driving the carriage in the opposite direction, each motor operable to drive the carriage through a different portion of its range of travel, and means to automatically connect the carriage with each

- motor as the carriage is brought within the carriage of travel controlled by said motor.

17. In a typewriting machine, the combination with a traveling carriage, of a motor operable to drive the carriage in one direction through one portion of its range of travel, a second motor operable to drive the carriage in the reverse direction through a different portion of its range of travel, means for automatically disconnecting the carriage from one motor when moved out of the range controlled by said motor, and means for automatically connecting the carriage with the other motor when brought within the range controlled by said other motor.

18. In a typewriting machine, the combination with a traveling carriage, of a motor for driving the carriage in one direction, a motor for driving the carriage in the opposite direction, draw bands to connect the motors with the carriage, and means to hold each draw band disconnected from the carriage while the carriage is driven by the other draw band.

19. In a typewriting machine, the combination with a traveling carriage, of a motor for driving the carriage in one direction, a motor to drive the carriage in the opposite direction, draw bands connected to the motors, hooks on said draw bands, and means on the carriage to selectively engage said hooks and connect each motor to the carriage during a different portion of the carriage travel.

20. In a typewriting machine, the combination with a plurality of type sets, of a traveling carriage to coöperate with one type set during a portion of its travel and to coöperate with another type set during another portion of its travel, a motor to drive the carriage in one direction when coöperating with one type set and in the opposite direction when coöperating with the other type set, an escapement mechanism controlling the movement of the carriage in one direction, a second escapement mechanism controlling the movement of the carriage in the other direction, and means for automatically connecting the carriage to each motor and escapement mechanism when the carriage is moved to a position to cooperate with the corresponding type set.

21. In a typewriting machine, the combination with a traveling carriage, of feed racks carried thereby, and having their teeth faced in opposite directions, pinions adapted to mesh respectively with said racks, escapement wheels connected to be driven by said pinions in opposite directions, and means to control the movement of said wheels.

22. In a typewriting machine, the combination with a plurality of type sets, of a traveling carriage movable into coöoperative relation to either type set, letter-feeding mechanisms controlled by said type sets, means for driving the carriage, said carriage being arranged to travel in one direction when in coöoperative relation to one type set, and in the opposite direction when in coöoperative relation to the other type set, and a plurality of feed racks on the carriage adapted to engage the respective letter-feeding mechanisms.

23. In a typewriting machine, the combination, with a track, of a carriage arranged to travel over the entire track, mechanism for effecting a letter-feeding movement of the carriage in one direction when traveling over one portion of said track, and separate mechanism for effecting a letter-feeding movement of said carriage in the opposite direction when traveling over another portion of said track.

24. In a typewriting machine, the combination, with a track, of a carriage arranged to travel over the entire track, mechanism for effecting a letter-feeding movement of said carriage in one direction when the carriage starts from one end of said track, and separate mechanism for effecting a letter-feeding movement of the carriage in the opposite direction when it starts from the other end of said track.

25. In a typewriting machine, the combination of a carriage movable through a plurality of distinct printing zones, key-controlled mechanism for effecting a letter-feeding movement of the carriage in one direction when said carriage is in one of said zones, and separate key-controlled mechanism for effecting a letter-feeding movement of said carriage in the opposite direction when the carriage is in another zone.

26. In a typewriting machine, the combination, with a carriage arranged to travel in either direction, of means to drive the carriage, letter-feed mechanism to control the movement of the carriage in one direction, and letter-feed mechanism independent of and remote from the first-named mechanism to control the movement of the carriage in the opposite direction, said carriage being movable from a position to cooperate with the other mechanism to a position to cooperate with the first-named mechanism.

27. In a typewriting machine, the combination, with a carriage arranged to travel in either direction, of means to drive the carriage, letter-feed mechanism to control the movement of the carriage in one direction, and letter-feed mechanism independent of and remote from the first-named mechanism to control the movement of the carriage in the opposite direction, said carriage being movable from a position to cooperate with the other mechanism to a position to cooperate with the first-named mechanism.

28. In a typewriting machine, the combination, with a carriage arranged to travel in either direction, of means to drive the carriage, letter-feed mechanism to control the movement of the carriage in one direction, and letter-feed mechanism independent of and remote from the first-named mechanism to control the movement of the carriage in the opposite direction, said carriage being movable from a position to cooperate with the other mechanism to a position to cooperate with the first-named mechanism.

29. In a typewriting machine, the combination, with a carriage arranged to travel in either direction, of means to drive the carriage, letter-feed mechanism to control the movement of the carriage in one direction, and letter-feed mechanism independent of and remote from the first-named mechanism to control the movement of the carriage in the opposite direction, said carriage being movable from a position to cooperate with the other mechanism to a position to cooperate with the first-named mechanism.

- separate bank of keys individual to each mechanism for actuating the same.
22. In a typewriting machine, the combination, with a carriage arranged to travel in either direction; of means to drive the carriage; letter-feed mechanism to control the movement of the carriage in one direction; letter-feed mechanism independent of and remote from the first-named mechanism to control the movement of the carriage in the opposite direction, said carriage being movable from a position to coöperate with either of said mechanisms to a position to coöperate with the other mechanism; and two banks of keys arranged side by side for actuating said mechanisms, one bank of keys individual to each mechanism.
23. A twin typewriting machine comprising two connected machine units each embodying a keyboard, an escapement mechanism controlled by the keys thereof, and a motor controlled by the escapement mechanism; a track extending across both of said units; and a single carriage mounted on said track to travel from end to end thereof, one of said motors being connectible with said carriage to drive the same in one direction, and the other motor being connectible with the carriage to drive it in the other direction.
24. A twin typewriting machine comprising two machine units connected side by side; a carriage mounted to travel from one unit to the other; key-controlled means for effecting a letter-feeding movement of the carriage in one direction during its travel across one machine unit; and key-controlled means for effecting a letter-feeding movement of said carriage in the opposite direction during its travel across the other machine unit.
25. In a typewriting machine, the combination, with a carriage; of a motor connectible with the carriage to drive it in one direction; a separate motor connectible with said carriage to drive the same in the opposite direction; escapement mechanism individual to each motor to control the drive thereof; and a set of actuating keys individual to each escapement mechanism.
26. In a typewriting machine, the combination, with a carriage; of a motor for driving the carriage in one direction; a motor for driving said carriage in the opposite direction; a key-actuated escapement mechanism individual to each motor for controlling the drive thereof; and means operable by the movement of the carriage to disconnect it from one motor and connect it with the other motor.
27. In a typewriting machine, the combination, with a carriage; of a motor connected with the carriage to drive it in one direction; a separate motor connected with said carriage to drive the same in the opposite direction; escapement mechanism individual to each motor to control the drive thereof; a set of actuating keys individual to each escapement mechanism; and means acting consequent upon the movement of the carriage to disconnect it from one motor and connect it with the other motor.
28. In a typewriting machine, the combination, with a carriage; of a pair of motors, one for driving the carriage in one direction, and the other for driving it in the opposite direction; a draw band connected to each motor and provided with a hook; and a pair of coupling members on said carriage acting simultaneously, one to engage one hook, and the other to release the other hook.
29. In a typewriting machine, the combination, with a carriage; of a pair of motors, one for driving the carriage in one direction, and the other for driving it in the opposite direction; a draw band connected to each motor and provided with a bifurcated hook; and a pair of coupling members on said carriage arranged to selectively engage in the bifurcations in said hooks and connect each motor to the carriage during a different portion of the carriage travel.
30.
